CLAIM

The ornamental design for a twin cavity hex bit, as shown and described.

DESCRIPTION

FIG. 1 is a perspective view of a twin cavity hex bit showing our new design;

FIG. 2 is a front perspective view thereof;

FIG. 3 is a front elevational view thereof;

FIG. 4 is a right-side elevational view thereof;

FIG. 5 is a rear elevational view thereof;

FIG. 6 is a left-side elevational view thereof;

FIG. 7 is a top plan view thereof;

FIG. 8 is a bottom plan view thereof;

FIG. 9 is a lateral view thereof;

FIG. 10 is a lateral view thereof, rotated 45 degrees from the position in FIG. 9;

FIG. 11 is a lateral view thereof, rotated 45 degrees from the position in FIG. 10;

FIG. 12 is a lateral view thereof, rotated 45 degrees from the position in FIG. 11; and,

FIG. 13 is a lateral view thereof, rotated 45 degrees from the position in FIG. 12.
